 hof, Germany, a company

Application May 12, 1939, Serial No. 273,313
 In Germany May 14, 1938

2 Claims. (Cl. 179—171.5)

The modulating circuits employed in carrier frequency systems must have a coefficient of non-linear distortion which with a high degree of modulation should be as small as possible. This requirement arises especially in the case of the so-called line radio, that is, systems in which speech, music, and the like is transmitted over telephone lines. The modulating circuits used in systems of this kind are in the nature of a bridge connection comprising rectifiers or amplifying tubes and have a current-voltage-characteristic which with small values greatly differs from the ideal characteristic necessary for obtaining a small coefficient of non-linear distortion. Therefore in such circuits the rectification in the case of high degrees of modulation, that is to say, in the case of high voltage amplitudes, will fail to be linear, thus producing distortion.

The present invention proposes to provide modulating circuits of this kind with a counter coupling adapted to render the modulation characteristic linear.

In the accompanying drawing two embodiments of the invention are illustrated.

Fig. 1 shows the circuit arrangement of one embodiment, while Fig. 2 is a diagrammatic representation of the other.

The modulator here shown by way of example comprises an input transformer U_1 over which the carrier frequency f_1 arrives, and also comprises rectifiers G_1, G_2 , such for instance as diodes or dry rectifiers, and an output transformer U_2 . The second or modulating frequency f_2 is conducted to the points A. The product of modulation of this bridge arrangement is amplified by an electron tube R and leaves the modulating arrangement over an output transformer U_3 .

Part of the output amplitude is conveyed through a phase and amplitude correcting device X to the transformer U_1 . The construction elements of the modulator are so calculated that the voltage returned by device X is in phase opposition with respect to the input voltage. By this means a counter coupling is produced that acts to decrease non-linear effects arising in the modulator.

The arrangement shown in Fig. 2 is a bridge type modulating circuit fitted with amplifying tubes. Also here the frequency f_1 is conveyed over transformer U_1 to a bridge B while the frequency f_2 is conveyed to this bridge over a transformer U. In the arms of bridge B amplifying tubes R_1, R_2 , such as triodes, for example, are included as non-linear members. On the output side the product of modulation is derived over transformer U_2 . The counter coupling is effected by the intermediary of phase and amplitude correcting devices Y_1, Y_2 by which the two sides of the output transformer are connected with the appertaining sides of the input transformer. An arrangement of this kind will not affect the symmetry of the modulating circuit and also allows of adjusting the properties of the said correcting devices independently of each other.

20 Equally, the modulation may be effected by means of an electron tube arranged to cooperate with an appropriate counter coupling.

What is claimed is:

1. A modulation arrangement comprising a balanced plurality of rectifier elements, a carrier input channel including a transformer, a signal input channel, an amplifier having an input and an output, means for applying carrier waves from said carrier input channel and signal waves from said signal input channel to said rectifier elements for modulating said carrier waves by said signal waves, connections for delivering from said elements to the input of said amplifier only carrier waves and modulation products, said connections being symmetrically arranged with respect to said signal waves so as to balance these out, and feedback means for feeding back carrier waves from the output of said amplifier to the primary side of said transformer in phase opposition to the waves supplied thereto from said carrier input channel whereby distortion is reduced.

2. An arrangement according to claim 1 wherein said amplifier is of unbalanced type and wherein said feedback means comprises unbalanced connections for effecting said feedback of carrier waves to said primary.

WOLFGANG HAGEN.
